STRINGED MUSICAL INSTRUMENT

Walter J. Pelensky, 19C Manheim Gardens,
Philadelphia, Pa. 19144

Filed Dec. 8, 1969, Ser. No. 20,399

Term of patent 14 years

Int. Cl. D17—03

U.S. Cl. D56—1

Fig. 1

Fig. 2

FIG. 1 is a perspective view of a stringed musical instrument, specifically an Ukrainian Bzhura, Bzura or Kobzura, showing my new design;

FIG. 2 is a face view; and

FIG. 3 is a left side elevational view thereof, the strings being omitted for convenience in illustration.

I claim:

The ornamental design for a stringed musical instrument, as shown and described.
